15 The accompanying drawing is a perspective view of my newly-designed ax box or case.

20 A is the box or case, wedge-shaped in outline and rectangular in plan view, being open at the side a, and having a thick heel or base, as shown, from which the lines of the top and

B is an inner lining of the same shape, open at the opposite side, as indicated by the dotted line b.

The design thus constitutes a neat, artistic, and useful receptacle of the shape and configuration shown in the drawing. 25
